(57) **CLAIM**

The ornamental design for a door component extrusion, as shown and described.

DESCRIPTION

FIG. 1 is a front isometric view of a door component extrusion showing our new design.

FIG. 2 is a front elevation view of the door component extrusion of FIG. 1.

FIG. 3 is a rear elevation view of the door component extrusion of FIG. 1.

FIG. 4 is a left side elevation view of the door component extrusion of FIG. 1.

FIG. 5 is a right side elevation view of the door component extrusion of FIG. 1.

FIG. 6 is a top plan view of the door component extrusion of FIG. 1; and,

FIG. 7 is a bottom plan view of the door component extrusion of FIG. 1.

In FIGS. 1–5 the door component extrusion is shown with a symbolic break in its length. The appearance of any portion of the door component extrusion between the break lines forms no part of the claimed design.
